UNITED STATES PATENT OFFICE.

GEORGE H. LANG, OF BOSTON, MASSACHUSETTS.

PRINTING-MACHINE.

1,017,979.

Specification of Letters Patent. Patented Feb. 20, 1912.

Application filed August 7, 1908. Serial No. 447,377.

To all whom it may concern:

Be it known that I, GEORGE H. LANG, a citizen of the United States, residing at Boston, county of Suffolk, and State of Massachusetts, have invented an Improvement in Printing-Machines, of which the following description, in connection with the accompanying drawing, is a specification, like characters on the drawing representing like parts.

This invention relates to printing machines and particularly to machines that are designed to print on cartons or boxes.

While the machine is adapted for printing on cartons which are used for a great variety of purposes, the machine has especial features which adapt it particularly for printing on paste-board shoe-boxes suitable data regarding the size and style of the shoes therein.

It is now the common practice to stamp on the end of each shoe box containing a pair of shoes suitable characters to indicate the style and size of the shoes within the box, the material of which they are made and sometimes other characters to indicate the style of the last on which the shoes are made and the case number. This stamping has universally been done by hand and when it is done in this way three or four separate operations are necessary, one operation being required to stamp on the box the character designating the style of the shoe, another operation being required to stamp the character designating the material of which the shoe is made, another operation being required to stamp the size of the shoe, etc.

By means of my present invention I have provided a printing machine having a series of adjustable type disks which have formed thereon the characters which it is desired to stamp on the carton, so that it is possible to stamp all the desired characters on a carton at one operation.

The printing head of the machine herein shown is made adjustable so that the different characters can be placed in different positions on the carton according to the wishes or custom of the party using the machine, and said machine is also adjustable in such a way that cartons of different sizes may be properly printed on.

The machine also includes other novel features of the invention which coöperate to produce an easily running and easily manipulated machine.

In the drawings I have illustrated a selected embodiment of my invention which shows the principle thereof, but I would state that the invention is not limited in all its details to the particular construction herein shown.

Figure 1 is a vertical sectional view through a machine embodying my invention; Fig. 2 is a front view of the printing head and the platen; Fig. 3 is a perspective view of the adjustable gage; Fig. 4 is a section on substantially the line a—a, Fig. 1, showing the manner in which the sections of the printing head may be adjusted; Fig. 5 is a side view of a portion of the printing head showing the auxiliary type-carrying member in operative position; Fig. 6 is a front view of Fig. 5; Fig. 7 is a perspective view of one end of a shoe-box or carton which has been printed on my improved machine; Fig. 8 indicates one series of characters that may be printed on the box.

The printing machine herein shown has the same general features as the printing machine shown in my Patents No. 864,790 and No. 877,653, that is, it comprises a printing head which is mounted on one end of an arm 3 that is pivoted to the frame 4, as at 5, the other end of said arm being connected by a link 6 with a crank disk 7. The crank disk is rigidly secured on a shaft 8 that has fast thereon a gear 9, said gear meshing with and being driven by a pinion 10 on the driving shaft 11. The pinion 10 is fast on the shaft and the latter has loose thereon a driving pulley (not shown) which can be clutched thereto by longitudinal movement of a clutch sleeve 12, all as more fully disclosed in said patents. This clutch sleeve is operated by a yoke 13 which is fast to a rock-shaft 14, said rock-shaft having an arm extending therefrom to which is secured a link 16 leading to a treadle, so that by operating the treadle, the link 16 is raised, thus rocking the shaft 14 in a direction to clutch the pinion 10 to the shaft 11. The rock-shaft 14 has fast thereon an arm 18 and the crank disk 7 has a recess 17 formed in the side face thereof, said recess being so positioned that when the printing head is elevated, as shown in Fig. 1, the recess comes opposite the arm, thus permitting the arm to be drawn into the recess by the spring 20, this movement of the arm and the rock-shaft 14 unclutching the pinion 10. The parts thus far described are or may be as found in

my said patents and form no part of my present invention.

The machine herein shown is especially designed for printing on the ends of shoe boxes, as shown in Fig. 7. Most shoe dealers stamp on the ends of the boxes suitable characters indicating the character of the shoe, the material of which it is made and the size of the shoe, and some shoe dealers also like to have printed on the box or carton a character indicating the style of the last and perhaps some other distinguishing characters. In order to permit these various characters to be printed on the carton, my present machine includes a plurality of series of type-disks, the type-disks of one series having the proper characters thereon for designating the character of shoe, the disks of another series having proper characters thereon for designating the kind of the material of which the shoe is made, and the disks of another series having thereon proper characters to designate the size of the shoe. In addition to this I have provided a series of type-disks having thereon the proper characters for designating an order number or a case number or some other distinguishing mark, and I have also made provision for printing on the box characters designating the style of the last. The various type-disks are shown as constructed similarly to the type-disks in my above-mentioned patents and are adjusted in a similar manner. Each type-disk is shown as mounted on a shaft and having rigid therewith a pinion 21 which meshes with and is operated by a segmental gear 22 provided with a thumb-piece 23 that extends through a slot in the numbering head so that by adjusting the thumb-pieces the disks can be set to bring any desired characters thereon into printing position. This manner of adjusting the type-disks is described and claimed in my above-mentioned patents and forms no part of the present invention. The carton or box 25 which is to be printed is sustained by a platen 26 during the printing operation, said platen being shaped so that the box can be inserted over it, with the end of the box resting on the top of the platen. The construction of the platen will be described more fully hereinafter.

Referring to Fig. 2, the type-disks bearing the type for designating the style of the shoe are indicated at 27, while those type-disks bearing the characters for designating the material of which the shoe is made are indicated at 28. The type-disks 27 may have thereon any desired characters, such, for instance, as BLU, FOX, BAL, BTN, COL, OX, TRN, TIE, and CON, etc., these characters being used to designate the terms blucher, foxed, bal, button, collar, oxford, turned, tie, congress, etc. The type-disks 28 may have thereon any suitable characters for

indicating the character of material of which the shoe is made, such, for instance, as PAT, VEL, GUN, RUS, WNE, BRN, KID, TAN, BOX, CAL, KAN, these abbreviations being used to indicate patent, velore, gun metal, russet, wine, brown, kid, tan, box calf, kangaroo. If desired all of the characters indicating the character of leather may be placed on one type-disk and all of the characters indicating the style of the shoe may be placed on another type-disk, but if there are a good many characters in each set, it may be desirable to distribute the characters of each set over two type-disks. By so doing it is possible to print a greater variety of characters because some kinds of shoes require two characters of the same set of characters to properly indicate the style of shoe. For instance, the shoe might be an Oxford and yet be of the Blucher pattern or be a Button shoe or a Tie shoe in which two characters of the same set would be necessary to indicate completely the style of the shoe.

The type-disks having characters thereon for indicating the size of the shoe are indicated at 29, and I have herein shown three such type-disks although any number desired may be employed. These type-disks are made to print numbers although they might be made to print letters without departing from the invention. I have also shown a series of type-disks indicated at 30 having suitable characters thereon for indicating the case number of the shoe, that is, the number of the case from which the pair of shoes in the box were taken. The type-disks 30 are arranged to print numbers or letters, or both, and each type-disk for printing numbers has thereon the digits 0 to 9.

In order to make the printing head capable of adjustment so that the different characters may be printed in different positions on the carton, I have made the printing head in sections and have arranged one or more sets of type-disks in each section. These sections are not only adjustable so that the position thereof may be changed but are also interchangeable. It is within my invention to make the printing head with any number of sections, but I find that all ordinary purposes are subserved by making it in three sections, as shown in Fig. 2. The three sections are designated 300, 31 and 32, respectively. The section 300 has therein the type-disks 30 for printing the characters designating the case number, the section 31 has therein the type-disks 27, 28 for printing the style of the shoe and the character of the material, and the section 32 has therein the type-disks 29 for printing the size of the shoe. Each section of the printing head is formed with two cheek pieces 33 which support the shaft 34 on which the type-disks are mounted and the

shaft 35 on which the segments 22 are mounted. Each section is complete in itself and any section can be adjusted relative to the other sections without disturbing any of the other sections. One simple way of supporting the various sections of the printing head so as to permit this to be done is shown in Figs. 1 and 4. The arm 3 has at its free end a cross piece or head 40 which is shown as slotted at 41, and which is provided with a longitudinally-extending groove 42. Each of the sections of the head is provided with a rib 43 to fit said groove and each section has screwed into it a clamping bolt 44 which extends through the slot 41. When any one of the clamping bolts is loosened the corresponding section of the printing head can be adjusted longitudinally of the slot and by removing the clamping bolts entirely from the sections they may be interchanged, that is, either section may be placed in any position desired. This making of the printing head in sections and making the sections independently adjustable and also interchangeable is an important feature of the invention because it provides a printing machine which can be used for printing on a great variety of different styles of shoe boxes.

30 My invention also includes a novel device for printing the half sizes. According to some systems the half sizes are indicated by placing an underscoring line beneath the size mark. A size mark without the underscore indicates the size expressed in whole numbers and with the underscore indicates the size expressed in fractional numbers. In order to permit the half sizes to be indicated in this way I have provided 35 an auxiliary type-carrying member which is arranged to print an underscoring line, and said member is constructed so that it can be thrown into and out of operative position as desired. This auxiliary type-carrying member is designated by 45 and is shown 40 as an L-shaped member loosely mounted on a stud 46 extending from the side of the printing head section 32. The horizontal portion 47 of said arm has thereon a character 48 arranged to print the underscoring line 49 shown in Fig. 8. Said horizontal arm is shaped to fit the V-shaped recesses 50 which are formed in the type-disks between the adjacent characters so 45 that when the arm is in operative position, as shown in Figs 5 and 6, it is held there by the V-shaped recesses. The auxiliary type-carrying member may be thrown into inoperative position by withdrawing it longitudinally of the stud 46 until the horizontal portion thereof is withdrawn from the type-disks 29 and then turning said member about the stud 46 into the dotted line position Fig. 5. Said member may be 60 held in its inoperative position by inserting the horizontal portion 47 into the loop 51 formed by the spring 52 which acts on the locking pawls 53 although this construction is not essential to the invention, as said member may be held in its inoperative position by any other means.

65 70 75 80 85 90 95 100 105 110 115 120 125 130

99 is a stop which serves to position the arm 45.

It is sometimes desirable to print on the carton a character indicating the style of the last in addition to the other character and to permit this to be done I have provided the printing section 32 with a block 530 which is adapted to removably sustain a plate 54 carrying type formed to print the character indicating the style of the last. In the particular instance illustrated in the drawing the last styles are indicated by proper names and the type on the plates 54 will, therefore, be formed to print such proper names. In Fig. 8 the word "Hooper" is the character indicating the style of the last, and the plate 54 will be cut to print this word. The plate 54 is made removable so that another plate may be substituted therefor and in the present embodiment this is provided for by making the ends of each plate beveled, as at 55, and confining said plate between two fingers 56, one on each side thereof. The plate is held in its proper position by means of a spring 57 acting on one end thereof. The plate can be readily removed by forcing the spring 57 backwardly sufficiently to permit the beveled end of the plate from being disengaged from the undercut groove in the block 530 in which it is received.

The platen 26 on which the box is supported is shown as a long comparatively thin bar which preferably has a rubber or yielding surface for the box to rest on. This platen is adjustably carried by a base piece 60 and is mounted for adjustment in the direction of the length of the line which is printed by the printing head. This adjustment is secured in the present embodiment by making said platen with the T-slot or groove 61 in which is received the head of a clamping bolt 62, said bolt extending down through the table 63.

The carton is properly positioned on the platen by means of a gage. One simple form of gage is shown in Figs. 1 and 3, and it comprises a head 64 having two projections 65 extending therefrom, said head being mounted on a slide 66 which fits in a groove formed in the base 60. The slide 66 is held in adjusted position by means of a clamping screw 67. This construction permits the gage to be adjusted toward and from the platen. In using the device, the box is placed over the platen with the end resting thereon and with the top edge of the box resting against the projections 65 of the

4
gage, said gage being properly adjusted so as to properly position the box. The position of the box is shown in dotted lines Fig. 1. The gage is made reversible, that is, 5 either end of the slide 66 may be inserted into the groove in the base. The head 64 is placed near one end of the slide and by placing one or the other end of the slide in the groove the gaging projections 65 may 10 be situated nearer to or farther from the platen as desired, depending upon the depth of the box and the position on the end thereof in which it is desired to print the characters.

15 While I have described my invention as it is used in printing distinguishing characters on the ends of shoe boxes, I wish it understood that the machine is adapted to print on boxes or cartons for containing 20 other goods, such, for instance, as hosiery, underwear, gloves, etc. It will be understood, of course, that where other cartons than shoe boxes are to be printed upon the type on the type-disks will be cut to print 25 the appropriate characters on the carton.

In the foregoing description I have used the expression "style of the shoe" to indicate the manner in which the shoe is made, that is, to indicate whether the shoe is an 30 Oxford shoe, a button shoe, a tie shoe, a Congress shoe, or a Blucher shoe.

Having fully described my invention, what I claim as new and desire to secure by Letters Patent is:

35 1. The combination with a printing head, of a platen support, an elongated platen sustained by said platen support and extending beyond the same at both sides thereof, said platen having a key slot extending longitudinally thereof in its under side and 40 open at one end thereof, and a clamping bolt carried by the support and having its head occupying said slot whereby the platen can be adjusted longitudinally and clamped 45 in any adjusted position.

2. In a printing machine, the combination with a printing head, of a platen shaped to have a carton placed thereover with one end of the carton resting on the platen, means to move the printing head toward and from the platen, and a reversible gage for positioning the carton, said gage being adjustable toward and from the platen and the platen being adjustable in a direction at right angles to that in which the gage is 55 adjustable.

3. In a printing machine, the combination with a printing head having a plurality of adjustable type-disks, of an auxiliary type-carrying member situated exterior to said 60 printing head, said member being movable in a direction parallel to the axis of the type disks to bring it into and out of operative position for printing.

4. In a printing machine, the combination with a printing head having a plurality of adjustable type-disks having type thereon to print characters indicating the whole sizes of shoes and an auxiliary type-carrying member situated exterior to the printing head and having type thereon of a character to indicate the half sizes, and means for sustaining said auxiliary member for movement in a direction longitudinally of the head to bring it into and out of operative position.

5. In a printing machine, the combination with a printing head comprising a casing having type-disks therein, of a stud extending from said casing, an auxiliary type-carrying member mounted on said stud and movable longitudinally thereon into and out of operative position.

In testimony whereof, I have signed my name to this specification, in the presence of two subscribing witnesses.

GEORGE H. LANG.
